F. F. & E. S. CAMERON.

TRANSMISSION GEARING FOR MOTOR VEHICLES.

APPLICATION FILED AUG. 13, 1906.

UNITED STATES PATENT OFFICE.

FORREST F. CAMERON AND EVERETT S. CAMERON, OF BROCKTON,
MASSACHUSETTS.

TRANSMISSION-GEARING FOR MOTOR-VEHICLES.

No. 841,373.

Specification of Letters Patent.

Patented Jan. 15, 1907.

Application filed August 13, 1906. Serial No. 330,481.

To all whom it may concern:

Be it known that we, FORREST F. CAMERON and EVERETT S. CAMERON, citizens of the United States, residing at the city of

5 Brockton, in the county of Plymouth and State of Massachusetts, have invented certain new and useful Improvements in Transmission-Gearing for Motor-Vehicles, of which the following is a specification.

10 This invention relates to improvements in transmission and reversing gearing, and is particularly designed for use in connection with a motor-driven vehicle.

The object of the invention is to provide a 15 simple, strong, and compact structure, which may be manufactured quite cheaply and may be readily taken apart to replace any of the parts which may have become worn or broken.

20 A further object of the invention is to provide an improved means whereby the adjustment of the sliding gears usually employed in this type of gearing for effecting a change of speed may be quickly and easily made, together with a novel means of locking said 25 gears in their adjusted position.

The invention consists of the novel features of construction and arrangement hereinafter more fully described, particularly 30 pointed out in the appended claims, and clearly illustrated in the accompanying drawings, in which—

Figure 1 is a top plan sectional view taken on line *a a* of Fig. 2, showing the general arrangement of parts embodying the invention; Fig. 2, a longitudinal sectional view taken on line *b b*, Fig. 1; Fig. 3, a transverse sectional view taken on line *c c* of Fig. 2, and Fig. 4 a top plan view.

40 Referring now more particularly to the drawings, the numeral 1 designates a casing formed of the two parts 2 2, bolted together in any well-known manner. The casing 1 is formed upon one of its ends with oppositely-disposed journal-bearings 3 3, arranged in direct alinement. In the bearings 3 3 are mounted the axle-tubes 5 5, carrying the stub-axles 7 7 and provided with the bevel-gears 8 8, meshing with the bevel-pinions 9 9, 45 mounted on the shaft 10, carried by the external ring-gear 16, the whole forming a compensating gear of well-known construction. At its opposite end the casing 1 is formed with a journal-bearing 4 for the reception of the

55 engine or power shaft 6. Mounted on the inner squared end of the engine-shaft is a bevel-gear 20, having the elongated cylindrical hub 35.

The opposite side walls of the casing are provided with guideways 36, having the bearing-surfaces 14. The numeral 37 designates a spider formed of the body portion 21 in the form of a square block, having a cylindrical bore and mounted on the extended hub 35 of the bevel-gear 20, being retained 60 thereon by means of the collar 22. The outer squared portion of the member 21 is seated in a correspondingly-squared portion of the casing 1, as shown at 38, and thereby held from rotation. The member 21 is provided with the two arms 13, formed at their outer ends with the enlarged portions 12, adapted to work within the guideways 36. Mounted between the arms 13 13 of the spider 37 is a square shaft 11, having its ends 70 rounded, as shown at 39, and journaled in the enlarged portions 12 of said arms. Slidably mounted on the shaft 11 is a large spur-gear 15, meshing with the ring-gear 16 of the compensating gearing heretofore described 75 and formed with the extended hub 40, on which are mounted the smaller graduated spur-gears 17 and 18. A large bevel-gear 19 is keyed on the shaft 11 and meshes with and is driven from the bevel-gear 20 on the engine-shaft 6.

80 From the foregoing description it will be seen that to effect a change of speed the gear 15 is moved longitudinally of the shaft 11 until spur-gear 17 is in alinement with gear 16 and the spider 37 forwardly until said gear meshes, and we will now describe the mechanism by which these two movements are accomplished simultaneously.

85 A rod 23, operated by a suitable foot-lever or other means, (not shown,) extends into the casing 1 at 41. The inner end of said rod is reduced and passes through one of the arms 13, as at 24, and is provided with the curved swinging arm 25. The outer end of the arm 100 25 is pierced to receive a stud 26 of the saddle-block 27, which is adapted to straddle the periphery of the spur-gear 15. If the rod 23 be given a partial rotation and at the same time moved longitudinally within the casing 1, the arm 25 will swing to the dotted position shown in Fig. 3, thereby moving the gears 15, 17, and 18 transversely on the shaft 105

11, and the spider 37 will move forwardly in its guideways until one of the spur-gears 17 or 18 meshes with the gear 16, thus reducing the speed thereof.

5 In Fig. 2 of the drawings is illustrated a device for locking the spider in any one of its adjusted positions. The squared portion 21 of the spider 37 is provided with a plurality of notches 29. Pivoted to the casing 1 directly above the member 21 is a pawl 28, having a pointed end adapted to seat in one of the notches 29, being locked therein by the action of the lever 30. Said lever 30 is pivoted intermediate its ends to the casing 1, one end thereof extending into the casing and its opposite end outside of the casing and connected to a pull-rod 31. The inner end of the lever is provided with a cam portion 42, adapted to bear against the pawl 28 and lock the same in one of the notches 29.

In order to reverse the motion of the gearing, we provide an auxiliary gear 32, mounted in the bifurcated end of a bell-crank lever 33, pivoted to the casing 1 in alignment with the gear 16. The opposite end of the lever extends outside of the casing and is connected to an operating-rod 34, actuated from a hand-lever at the side of the car. (Not shown.) The operation of the reversing is accomplished as follows: The rod 23 is given a partial rotation, which moves gear 15 transversely on the shaft 11, until the small spur-gear 18 is in alignment with the ring-gear 16. A pull on rod 34 then throws spur-gear 32 in between the gears 16 and 18, and the motion of said gear-wheel 16 is reversed.

We claim—

1. In a transmission-gearing, the combination of a casing; axle-tubes journaled therein and provided with a compensating gearing; a ring spur-gear carried by the compensating gearing; a driving-shaft journaled in said casing and disposed at right angles to the axle-tubes; a beveled gear fixed on the driving-shaft; a sliding frame mounted in the casing and embracing the driving-shaft; an intermediate shaft journaled in said frame; sliding spur-gears fast on last-mentioned shaft and adapted to mesh with the ring spur-gear; a second beveled gear fast on last-mentioned shaft and in mesh with first-mentioned beveled gear, and means for simultaneously actuating said sliding gears and frame.

2. In a speed-changing device of the character described the combination with the casing; axle-tubes journaled therein and provided with a compensating gearing; a ring

spur-gear carried by the compensating gearing; a spider slidably mounted in said casing; a flat-sided shaft journaled in said spider; spur-gears slidably mounted on said shaft; a power-shaft; a beveled gear fast on last-mentioned shaft; a second beveled gear fast on first-mentioned shaft and engaging first-mentioned beveled gear; an operating-rod passing through said casing and said spider; a swinging arm secured upon said rod, and a saddle-block carried by said arm and arranged to straddle the peripheral portion of one spur-gear on first-mentioned shaft.

3. In a transmission-gearing, the combination with a casing; axle-tubes journaled therein and provided with a compensating gearing; a ring spur-gear carried by the compensating gearing; a driving-shaft; a beveled gear fast on said shaft and having an integral circular hub; a collar fast on the hub of said beveled gear; a spider having an integral block slidably mounted in said casing and embracing the hub of said beveled gear, and the block of said spider provided with notches; a flat-sided shaft journaled in said spider; spur-gears slidably mounted and fast on last-mentioned shaft; a second beveled gear fast on last-mentioned shaft and in mesh with first-mentioned beveled gear; a pawl pivoted to the casing and adapted to seat in the notches of said spider; a cam-lever pivoted on the casing and bearing on said pawl, and a pull-rod for operating said lever.

4. In a speed-changing and reversing gearing, the combination with the casing; axle-tubes journaled therein and provided with a compensating gearing; a ring spur-gear carried by the compensating gearing; a driving-shaft; a beveled gear fast on said shaft; a frame mounted in said casing; a flat-sided shaft journaled in said frame; a series of spur-gears slidably mounted fast on last-mentioned shaft; a beveled gear fast on last-mentioned shaft and in mesh with first-mentioned beveled gear; a bell-crank lever pivoted to the casing; a spur-gear carried thereby, and a rod connection from said lever to operate in carrying said last spur-gear into or out of engagement with the smaller spur-gear of the series on last-mentioned shaft.

In testimony whereof we affix our signatures in presence of two witnesses.
